DESIGN FOR A TOY TANK

Ernest P. Lutz, Los Angeles, Calif., assignor of one-half to Julian M. Cowell, Los Angeles, Calif.

Application February 22, 1944, Serial No. 112,673

Term of patent 7 years

(Cl. D34—15)

To all whom it may concern:

Be it known that I, Ernest P. Lutz, a citizen of the United States, residing at 1411½ Murray Drive, in the city of Los Angeles (26), county of Los Angeles, and State of California, have invented a new, original, and ornamental Design for a Toy Tank, of which the following is a specification, reference being had to the accompanying drawing, forming part thereof.

Fig. 1 is a side elevation of a top tank, showing my new design,

Fig. 2 is a plan view of the toy,

Fig. 3 is a front elevation of the toy, and

Fig. 4 is a rear view of the toy.

I claim:

The ornamental design for a toy tank, as shown.

ERNEST P. LUTZ.
